UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 21,959, dated November 8, 1892.

Application filed October 10, 1892. Serial No. 448,442. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification, reference being had to the accompanying drawing, forming part thereof.

10 The leading feature of this design consists of ornamental scrolls of the French renaissance style running vertically through the design with festoons of flowers and leaves suspended by ribbons from said scroll ornaments and hanging horizontally over said ornaments, as represented in the accompanying drawing.

The design is printed in any desired color or colors or in gilt or bronze and color upon tinted paper of any desired color and is designed for a wall decoration.

What I claim is—

The design for wall-paper herein shown and described.

Witness my hand this 7th day of October, 25
1892.

CHARLES BOOZE.
